UNITED STATES PATENT OFFICE

WILLIAM R. HOTCHKISS, OF ST. PAUL, MINNESOTA

BLANK-BOOK

Application filed August 13, 1932. Serial No. 628,657.

This invention relates to blank books of the permanently bound type wherein it is desired to write both on stub or permanent record portions and on the main or removable portions of the sheets.

In all of the old books of this type with which I am familiar the writer is hindered to some extent in making entries on the stubs or elsewhere in the book by the necessity of holding the stubs of previously issued sheets out of the way or by other obstruction.

It is my object to provide a novel and improved blank book wherein associated portions of the leaves, such as stubs and removable portions, are both readily accessible and unobstructed for writing when the book is opened at any point therein.

A further object is to provide an unusually inexpensive, permanently bound book, suitable for use as a check book, and having the advantages above pointed out.

Referring to the accompanying drawings, wherein the invention is illustrated as applied to a check book;

Figure 1 is a plan view of the book in open position;

Fig. 2 is an enlarged side view with the leaves closed and showing the binding;

Fig. 3 is a fragmentary, enlarged plan view of the book in open position and

Fig. 4 is a section taken on the line 4-4 of Fig. 3.

The book is formed from a multiplicity of sheets, each folded along a line 5 to produce a stub or permanent record portion 6 and a main or removable portion 7 at opposite sides respectively of the line 5. The portions 6 and 7 have printed on their inner faces suitable lines and legends as a guide to the entries to be written thereon. Extending parallel to the fold lines 5 and on the outer faces of each fold (viz., on the side reverse to the printing) are narrow bands 8 of adhesive for securing the sheets together in a permanently bound pad or book. The securing means are preferably spaced slightly from the fold lines 5 to permit expansion of the book in the direction of its thickness and to give flexibility, permitting ready

opening of the book. To facilitate removal of the checks as they are issued the portions 7 of the sheets are perforated along lines 9 extending parallel to the fold lines 5, the adhesive being located between said lines 9 and 5. The line 9 of perforations defines a narrow binding portion of the leaf having the checks printed thereon and also constitutes a second fold line to facilitate folding the checks or turning the leaves on which they are printed so that endorsements or other matter may be conveniently written on the backs of the leaves. The backs or outer surfaces of the sheets would otherwise be relatively inaccessible because of the necessity for manual holding of the check portion of one sheet away from the back of the stub portion of the adjacent sheet with my type of binding. Where a plurality of checks or other forms are provided on each sheet, as illustrated in Fig. 1, the several forms may be separated by lines of perforations 10 of the usual or suitable type.

The book may be opened at any point between the printed faces of the sheets by unfolding, as indicated in Fig. 4, to position the permanent record portion 6 of a sheet directly opposite the associated portion 7. When in this open position the top sheets lie flat and are without obstruction of any kind to writing on either fold. It will be evident that unobstructed writing surfaces remain even after a number of the removable portions of the sheets have been withdrawn from the book.

If desired, stiff covers and additional binding at the back of the book may be furnished without interfering with the operation of the device. Obviously the device may be used for books of various kinds in addition to check books such, for example, as stock record books, receipt books pads of coupons and of numerous banking forms.

Having described my invention, what I claim as new and desire to protect by Letters Patent is:

1. A blank book having in combination a multiplicity of sheets each folded upon itself and having narrow bands of adhesive

securing said folded sheets together on their outer surfaces and along lines parallel to and spaced from the fold lines, the portions of the sheets closely adjacent to the fold lines being free for limited separation from each other.

2. A blank book having in combination a multiplicity of sheets each folded upon itself and means for securing said folded sheets together adjacent to the fold lines to form a book wherein the several folded sheets may be unfolded to simultaneously present the inner faces of both folds for writing and one of the folds of each sheet having a line 15 of perforations parallel to the fold line and closely adjacent to said securing means to form a second fold line.

3. A blank book having in combination a multiplicity of superimposed and separately 20 folded sheets, each having on the inner face of one fold a permanent record portion and on the inner face of the other fold a removable portion associated with said record por-

tion and a narrow band of adhesive extending along the fold line of each sheet for securing said folded sheets together adjacent to the fold lines and the removable portion of each sheet having a line of perforations spaced from the fold line beyond 70 said band of adhesive.

4. A blank book having in combination a multiplicity of superimposed and separately 75 folded sheets, each having blanks for written matter on the inner face of each leaf and a narrow band of adhesive extending along the exterior surface, adjacent to the fold line, for binding the sheets together and one leaf of each sheet having a line 80 of perforations spaced from the fold line beyond said band of adhesive and defining a narrow binding portion and a second fold line along which said leaf may be folded to present a flat writing surface on the outer 85 surface of the sheet.
